Primary Examiner — Darlington Ly(74) *Attorney, Agent, or Firm* — Kofi A. Schulterbrandt(57) **CLAIM**

The ornamental design for a nut fastening tool, as shown and described.

DESCRIPTION

FIG. 1 is a top and rear perspective view of a nut fastening tool embodying my new design;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof; and,

FIG. 7 is a bottom plan view thereof.

Broken lines illustrate portions of the nut fastening tool and form no part of the claimed design.
